UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIE-SEPARATING MEANS.

Application filed October 31, 1921. Serial No. 511,801.

To all whom it may concern:

Be it known that I, RICHARD LESTER WILCOX, a citizen of the United States, residing at Waterbury, in the county of New Haven and State of Connecticut, have invented certain new and useful Improvements in Die-Separating Means, of which the following is a specification, reference being had therein to the accompanying drawings.

My invention relates to die separating means, its principal object being to provide simple mechanism for separating the dies of an open die header or upsetting machine.

Among other aims and objects of my invention may be recited the provision of a device of the character mentioned with a view to compactness and in which the number of parts are few, the construction simple, the cost of production small, and efficiency and operation high.

The improvements in the details and arrangement of parts will be apparent from an inspection of the accompanying drawings, in connection with the description herein-after contained, and wherein an embodiment of the invention is disclosed for the purpose of imparting a full understanding of the same.

Having more particular reference to the drawings and in connection with which like reference characters refer to corresponding parts in the several figures;

Figure 1 is a front view of a pair of dies of a heading machine or the like and a fragmentary portion of its supporting mechanism, with my improved means connected therewith;

Figure 2 is a sectional elevation thereof taken generally upon line 2—2 of Figure 1;

Figure 3 is a detail sectional view of the mechanism taken generally upon line 3—3 of Figure 2;

Figure 4 is a fragmentary sectional view similar to that shown in Figure 2, but modified slightly in its construction; Figure 5 is a front view of a pair of dies similar to those shown in Figure 1 with the separating mechanism applied to the underside of the dies; and Figure 6 illustrates a modified form of separating plate.

It has heretofore been the practice to separate the dies of an open die header or upsetting machine at the wire feed line by parting pins, separating pins or the like, an

illustration of such means being shown in 55 Letters Patent No. 1,104,090, dated July 21, 1914, particularly in Figure 4 thereof, and also in Letters Patent No. 1,108,958, dated September 1, 1914, a heavy flat spring, not shown in either of the above patents, bearing 60 upon the upper end of each of the parting pins or separating pins, which move in a path at substantially a right angle to the movement of the dies. With such mechanism the die cap or other part or parts that 65 support the pins must be machined with great care and exactness and each must be in correct alignment with each other and the groove formed by the angular corner faces of the dies, when the dies are in proximity to the wire feed line. If the pins are not so arranged, the lower pointed end thereof will not register with said groove, thus having a tendency to cramp the dies and apply 70 an unequal pressure thereto at different points throughout their length. If this occurs, the dies may be separated more at one end than at the other, and if perchance the minimum separation is at the inner end of the dies a defective feed of the wire results 75 and the end of the wire may abut against the dies and stop the feed.

With the use of such pins the spring pressure upon the end thereof is constant, therefore it requires not only a pressure sufficient 80 to move the dies and cut off the wire but also to resist the pressure of the pin actuating springs, which pressure is constant upon the top of one of the dies during its 85 entire movement. There is no use for this pressure except when the dies are to be separated at the wire feed line, hence more power is necessarily required to actuate the dies. While more powerful mechanism is required to move the dies from the wire feed 90 line to the upsetting line, the dies are usually returned by spring pressure, the strength of which must of necessity also be increased to overcome the needless drag and pressure of the pins.

As the pins are of substantial length the element in which they are mounted must of necessity be of substantial height to provide proper support therefor and this height, as well as the pin operating springs, requires 95 space that can otherwise be advantageously utilized.

All of the above and other objections of

the heretofore conventional method for separating the dies are obviated in my improved device, which occupies the minimum amount of not otherwise required space, pressure is applied only when the dies are to be separated, the necessity of fine machining of the parts is entirely eliminated, and in these, and many other ways, produces results that are advantageous and insure certainty and efficiency in operation, and with mechanism that is of comparatively simple design.

Having more particular reference to the drawings, numerals 10 and 11 represent the dies, which are of the usual form with corner angular faces 12 which unite to form a V-shaped groove substantially as shown in Figures 1 and 3, wherein the dies are near the wire feed line, this being coincident with the line 2-2 of Figure 1. A piece of wire designated 13 is shown in section at this feed line.

The bed plate upon which the dies are supported is designated 14, and the cap or cover over the top thereof 15.

All of the mechanism above described is of a well known form and operates in an equally well known manner and therefore needs no further description herein.

The means for actuating the dies is not shown herein for the above reason, but the same travel between the wire feed line and the upsetting line, which latter line is designated x-x in Figure 1. From the wire feed line to the upsetting line the dies are positively actuated by relatively powerful mechanism to cut off a piece of the wire rod but are usually returned from the upsetting line by spring mechanism.

Referring now particularly to Figures 1 to 4, inclusive, the cover 15 is provided with a recess 16 having one angular wall 17 and a straight wall 18 joined by a curved wall 21, and within which is a plate 19 loosely mounted, which latter is preferably rounded at each end. Endwise movement of this plate within the recess 16 is prevented by the cap 20 connected with the cover 15 or other suitable means as by a lip 22 formed on the cover 15, as shown in Figure 4.

The position of the plate 19 is shown by full lines when the dies are at rest near the wire feed line, at which time the upper rounded end of the plate engages the curved wall 21 at the top of the recess 16 and the lower rounded end is within the V groove formed by two of the angular faces 12 of the dies 10 and 11. When the parts are thus arranged the dies 10 and 11 are a slight distance apart so as to admit a proper feed of the wire 13 therebetween. When the dies move from this position to the upsetting line the plate 19 travels therewith until it assumes the position in the recess 16 substantially as shown by broken lines in Figure 1, where it exerts no influence upon either

of the dies. However, when the dies are returned from the upsetting line to the wire feed line and are approximately at the latter line, the upper rounded end of the plate 19 engages the rounded wall 21 of the recess 16 and by fulcruming thereon moves the lower rounded end downwardly a limited distance and forces the dies apart, until one face thereof abuts against the straight wall 18 of the recess 16, at which time the dies are separated the required distance. Thus my improved die separating mechanism requires a minimum amount of space, pressure is only applied when required, that is, when the dies are at or near the wire feed line, and in these and other ways, the objections to the mechanisms heretofore commonly utilized for separating the dies are eliminated and many obvious advantages secured.

I have shown in Figures 1, 2 and 4 my improved mechanism as applied to the top side of the dies but obviously it will operate equally as well if applied to the underside thereof as shown in Figure 5, or if desired, it may be used upon both top and bottom. If used upon the bottom the plate 19 is mounted in the bed plate 14 instead of the cap or cover 15.

The ends of the plate 19 may, if desired, be V shaped or otherwise formed as shown in Figure 6, instead of rounded as above described.

There are minor changes and alterations that can be made within my invention, aside from those herein suggested, and I would therefore have it understood that I do not limit myself to the exact construction herein shown and described, but claim all that falls fairly within the spirit and scope of the appended claims which do not include a structure wherein the plate is pivotally mounted.

Having described my invention, what I claim as new and desire to secure by Letters Patent is:

1. In combination with dies of a heading machine or the like, means for supporting the same; and means for separating said dies, comprising a plate lying within a recess in an adjacent part and moved by said dies so as to engage one end of said recess and be wedged between said dies at a predetermined point in the movement thereof.

2. In combination with dies of a heading machine or the like, means for supporting the same; and means for separating said dies, comprising a plate lying within a recess in an adjacent part and moved by said dies so as to engage one end of said recess and be wedged between said dies at a predetermined point in the movement thereof; and means for preventing endwise movement of said plate.

3. In combination with the dies of a heading machine or the like movable be-

tween two walls toward and away from a wire feed line, one of the walls having a recess therein; a plate movable within said recess during the movement of said dies

5 until the same are approximately at the said wire feed line, when said plate engages one wall of said recess, and is wedged between and separates said dies.

4. In combination with the dies of a heading machine or the like; a recessed member adjacent thereto; said recess having one substantially straight wall; a plate movable within said recess with said dies until the same are approximately at the wire

15 feed line when said plate engages the straight wall of said recess, and is wedged between said dies and separates the same.

5. In combination with the dies of a heading machine or the like; a recessed member adjacent thereto; the recess having a substantially straight wall and another wall at an angle thereto; and a plate movably mounted within said recess and when in contact with said straight wall, one end

25 thereof is between said dies and separates the same.

6. In combination with the dies of a heading machine or the like movable between two walls toward and away from a wire feed

30 line, one of the walls having a recess therein a plate movable within said recess during the movement of said dies, until the same are approximately at the said wire feed line, when said plate engages one wall of said recess, and is wedged between and separates said dies, and means for closing the outer end of said recess.

7. In combination with the dies of a heading machine or the like; a recessed

40 member adjacent thereto; said recess hav-

ing one substantially straight wall; a plate round at both ends movable within said recess with said dies until the same are approximately at the wire feed line when said plate engages the straight wall of said recess, and is wedged between said dies and separates the same.

8. In combination with the dies, of a heading machine or the like having angular faces on the corners thereof; a member having a recess therein adjacent thereto; and a plate slightly longer than the depth of said recess and movable laterally within the recess by the dies.

9. In combination with the dies, of a heading machine or the like; that move toward and away from a station; a member adjacent thereto having a recess therein of varying depths, the deepest portion of which is substantially in register with said station; a plate movable within said recess by said dies while traveling toward and away from the station the inner end of which projects between said dies when the same are at said station and separates the dies.

10. In combination with the dies of a heading machine or the like; a member having a recess therein adjacent to said dies; a plate movable within said recess and having engagement with said dies, one of which engages the end of said plate and moves the same against one wall of said recess and by reason thereof moves the opposite end between said dies and thereby separates the same.

In testimony whereof, I have hereunto affixed my signature.

RICHARD LESTER WILCOX.
